UNITED STATES PATENT OFFICE.

ERNEST E. EINFELDT, OF DAVENPORT, IOWA, ASSIGNOR, BY MESNE ASSIGNMENTS, TO FRENCH & HECHT, INC., OF DAVENPORT, IOWA, A CORPORATION OF IOWA.

METHOD OF MAKING METAL WHEEL RIMS.

Original application filed February 29, 1924, Serial No. 696,013. Divided and this application filed September 29, 1924, Serial No. 740,434.

This invention relates to the production of metal wheels and has reference more particularly to the formation of a wheel rim in order to produce traction lugs thereon to give the 5 wheel tractive qualities.

The object of the invention is to form on the rim of the wheel by a bending or deforming operation on the metal, traction lugs of maximum height with a minimum bend or 10 displacement of the metal; and to this end the invention consists of the improved method in which the marginal edges of a blank are bent at intervals alternately in opposite directions to give said edges a wavy outline and thereby 15 produce traction lugs thereon.

In the accompanying drawings:

Fig. 1 is a cross sectional view of a blank suitable for carrying my invention into effect in producing a wheel rim of one form. 20 Fig. 2 is a side elevation of the same after the marginal edges are bent in accordance with my invention to produce traction lugs, the said figure showing the bent rim connected with the spokes of a wheel. 25 Fig. 3 is a cross section of the same.

Fig. 4 is a plan view of the bent rim. 30 Fig. 5 is a cross sectional view of a blank suitable for the practice of my invention in producing a wheel rim of a different form.

Fig. 6 is a side elevation of the same after the marginal edges of the blank are bent, the said figure showing the bent rim connected with the spokes of a wheel. 35 Fig. 7 is a cross section through the same.

Referring to the drawings: 35 In carrying my invention into effect in producing a wheel rim of the form shown in Figs. 2 to 4, a sheet metal blank A is provided as shown in Fig. 1, which is formed with a 40 central circumferential groove 1, and which is given the arcuate form in cross section as shown. The marginal edges of the blank are now by suitable means or devices bent alternately in opposite directions from a common 45 base line represented by the edges 2, said edges being bent each upwardly at intervals as indicated by the dotted line 3 at the right of the figure, and being bent downwardly at intervals as indicated by the dotted line 4 at 50 the left of the figure, thereby producing the oppositely facing depressions or cavities 5 and 6 and the traction lugs 7 as shown in Figs. 2 and 3. The metal is so manipulated in the bending operation that the depressions and

projections will be disposed transversely of 55 the rim, will be of the greatest depth at the marginal edges thereof, and will gradually decrease in depth towards the center of the rim where they will vanish in the central 60 tread portion.

The effect of the formation of the marginal edges of the rim as described, is to give said edges a wavy outline and produce corrugations which join each other and which extend continuously around the entire circumference 65 of the rim. This formation produces a construction of great strength and stiffness and enables the maximum height of traction lug to be formed with a minimum bend or displacement of the metal. It will be observed 70 that due to the bending of the marginal edges of the blank alternately in opposite directions as described, a portion of the effective height of the traction lugs is given by the bending of a section of the metal in one direction, and the 75 remaining portion is given by the bending of an adjacent section of the metal in the opposite direction, so that a given section of the metal is displaced for substantially half of 80 the height of the lug produced. This method 85 of procedure produces a rim which is of great stiffness and strength throughout its transverse and circumferential extent, and is free from the weakness which would be created by an undue stretch or bending of the metal. 85

With reference to Figs. 3 and 4 it will be seen that the two series of depressions and corresponding projections forming the traction lugs at the opposite edges of the rim, terminate at their inner adjacent ends 90 in the side walls of the groove 1, slightly intersecting the same and thereby producing slight projections 8 on said walls at intervals around the rim. These walls of the groove constitute the central tread portion 95 of the rim, which tread portion travels on hard roads or ground with no roughness of travel except as produced by the slight projections 8, but on softer roads or soil, the tread portion sinks and the traction lugs are 100 brought into action.

The result of the practice of the method as described in connection with a blank of the form shown in Fig. 1 is the production of a wheel rim arcuate in cross section and crowned or convexed on its outer side. In Figs. 6 and 7 a rim is shown produced 105 by my improved method, which while also

arcuate in cross section, is of the opposite transverse curvature, or in other words is concave on its outer side. To produce a rim of this form, a blank B of the form 5 shown in Fig. 5 is provided which is curved inwardly between its circumferential edges so as to present a transverse concavity at its outer face, and the marginal edges of the blank are bent alternately outwardly 10 and inwardly, as in the first case described, from a base line represented by the edges 9 of the blank, respectively to the dotted line positions 10, thereby producing the oppositely facing depressions 11 and 12 and 15 the traction lugs 13 as shown in Figs. 6 and 7. And similarly in this case, the effect of the practice of the method is to form the marginal edges of the blank wavy in outline and produce corrugations in the rim 20 joining each other and extending continuously around the entire circumference.

While in the foregoing description and accompanying drawings I have set forth my improved method of procedure as embodying the specific steps described suitable 25 for the ends in view, it will be understood that these steps of procedure may be changed and modified without departing from the spirit of the invention; and it will be understood that the invention is not limited to the exact method of procedure set forth 30 except in so far as such limitations are specified in the claims.

Having thus described my invention, what 35 I claim is:

1. The method of shaping a sheet metal blank to form a wheel rim with traction lugs, which consists in bending the marginal edge of the blank at intervals alternately in opposite directions from a com- 40

mon base line coincident with said marginal edge before bending, to produce traction lugs thereon having an effective height substantially greater than the extent of bend of the metal in one direction. 45

2. The method of shaping a sheet metal blank to form a wheel rim with traction lugs, which consists in first giving said blank an arcuate form in cross section, and then bending the marginal edge of the arcuate blank, at intervals alternately in opposite directions from a common base line coincident with the edge of the arcuate blank before bending, to produce traction lugs thereon having an effective height substantially 50 greater than the extent of bend of the metal in one direction. 55

3. The method of shaping a sheet metal blank to form a wheel rim with traction lugs, which consists in forming in the blank a longitudinal groove and giving said blank an arcuate form in cross section, then bending the marginal edge of the blank at intervals alternately in opposite directions from a common base line coincident with the edge 60 of the blank before bending to produce transversely extending depressions and corresponding projections constituting traction lugs having an effective height substantially 65 greater than the extent of the bend of the metal in one direction, and so manipulating the metal in the bending operation that the depressions and projections will be of the greatest depth at the marginal edge of the blank and will decrease in depth toward 70 the groove and will vanish in said groove. 75

In testimony whereof, I have affixed my signature hereto.

ERNEST E. EINFELDT.
